UNITED STATES PATENT OFFICE

HARCOURT CORY HANROTT, OF WESTMINSTER, LONDON, ENGLAND

PERPETUAL CALENDAR

Application filed January 27, 1931, Serial No. 511,609, and in Great Britain February 5, 1930.

This invention relates to improvements in perpetual calendars in which provision is made for crossing out or cancelling expired dates by means of a transparent cancellation web having a series of opaque lines in echelon ruled upon it, which are advanced day by day by moving the web across the month sheet to cross out the day numeral just expired.

10 According to the present invention the calendar comprises a casing, a month sheet visible through an aperture in the casing, and a cancellation disc, on which the cancelling lines are arranged as a series of interrupted 5 concentric circles, mounted to rotate between the wall of the casing and the month sheet.

The month sheet, on which the various calendar months are written, is preferably mounted in the casing so as to enable it to be 20 readily adjusted, when it is necessary to change the month.

The month sheet may consist of a rotatably mounted disc but in the preferred construction it is removably positioned between the 25 front and back of the casing. For this purpose the back of the casing may be detachable or an opening is provided along one edge through which the month sheet can be removed. The month sheet has printed thereon 30 the various calendar months grouped around and arranged concentrically with the axis of rotation of the cancellation disc.

The names of the month may be arranged on another rotatably mounted (third) disc or 35 a sheet that is adjustable.

In the preferred embodiment of the invention the cancellation disc is located at the back of the front of the casing and is secured to a spigot passing through an aperture in the 40 front and integral with an operating knob.

The third disc is rotatably mounted on the front side of the back of the casing by means of a hollow rivet and the names of the months printed thereon are visible through apertures 45 cut in the month sheet adjacent each calendar

month and through the cancellation disc which is formed of celluloid, and also through the aperture in the front of the casing, this latter aperture being of such size as to enable a single calendar section being visible. 50

When it is desired to change the calendar section which is visible through the aperture in the casing front, the month sheet is slid out of the casing (or the back of the casing removed) and the month sheet is then turned and re-inserted with the desired calendar section visible through the aperture. To enable the third disc to be rotated to bring the required month name in line with its aperture, the back of the casing has also formed therein an arcuate slot to enable the third disc to be turned by thumb or finger. 55 60

It will be understood that the casing is of such size as to contain the cancellation disc and the third disc without distortion thereof. In order however, to diminish the height of the casing, more especially in the case of a desk model the axis of rotation of the cancellation disc may be lowered. This is rendered possible by forming the disc of flexible material and bending its lower periphery out of the vertical plane, the casing being provided with a housing or base portion into which the periphery of the disc extends. 70 75 This entails a corresponding lowering of the month sheet.

The invention is illustrated in the accompanying drawings in which:—

Figure 1 is an elevation of a perpetual calendar,

Figure 2 being a rear view with the back and base of the casing removed.

Figure 3 is a vertical section of the calendar. 85

Figure 4 is an elevation showing the back of the casing from the rear and the month disc carried thereby.

Figures 5 and 6 are detail views of the 90

month name disc and month sheet respectively.

In the drawings the calendar comprises a mounting or casing having a front 1 and a back 2. The front 1 of the casing is formed with an aperture 3, through which a cancellation disc 4, month sheet 5, and month name disc 6 is visible. The cancellation disc it will be appreciated is formed of transparent material, such as celluloid, and the gaps between the ends of each successive cancelling line, one of which is indicated at 5', increase in size from the outer to the innermost circle each increase being equal to the distance apart, measured along a circumference of the numerals representing seven days of the week written on the month sheet. The disc 4 is secured to an operating knob 7 which has a bearing at 8 in a cut out portion of the front 1 of the casing. Secured to the rear of the front 1 is a base piece 9 (see Figure 3) which is hollow for the reception of the periphery of the disc 4 and the lower side of the month sheet 5. It is obvious that this arrangement permits the vertical height of the casing to be diminished and moreover the base piece 9 functions also to support the casing, although this is not essential as it may be supported by a hinged flap in the usual manner.

The casing at its base may in some cases conveniently terminate in a pen rest or such like receptacle (not shown).

With a hanging wheel where the vertical dimension is not of importance, the base piece 9 is eliminated and the size of the casing correspondingly increased.

The rear of the front 1 is cut away at 10 to form a recess for the reception of the back 2 and lugs 11 are provided for positioning the month sheet 5. Securing pieces are also mounted on the lugs 11 for holding the back in place. The back 2 is shaped to fit into the recess in the front and so as to clear the lugs 11. 12 is a slot to enable finger or thumb adjustment of the month name disc 6 which is rotatably mounted at 13. Alternatively the disc 6 may be operated by means of a knob.

Referring to Figure 6 the month sheet has printed or otherwise written on it the various calendar months, and when in position it is located between the cancellation disc 4, and month name disc 6, slots 14 being cut in it beneath each calendar month to enable the month name to be read. While the month name is visible through the aperture 3, a separate aperture may of course be provided in the casing through which the month names are visible. 15 are notches cut in the sides of the month sheet to ensure its proper registration with the cancellation disc 4 and with the month name disc 6. It will be understood that while the form of month sheet as illustrated is preferred, a fixed month

sheet may be provided and the days of the week adjustable with respect thereto as is usual in certain types of perpetual calendars.

If desired the calendar may be constructed to show the year, by means of a year card, or adjustable numbers may be provided for this purpose. Likewise or alternatively, and particularly in the case of a "hanging" calendar where more space is available, two changeable sets of numbers may be provided to show separately the date of the month. Two discs of numbers, adjustable by finger knobs from the front of the casing, and visible through an aperture therein, may be rotatably carried on the back of the front 1 of the casing.

The figures on these discs are preferably comparatively large in size for distance vision.

What I claim is:—

1. In a perpetual calendar of the type set out, the combination of a casing, said casing having an aperture in the front thereof, a detachable back on the casing alignment lugs on the casing, a month sheet visible through the aperture in the casing, a cancellation disc having cancelling lines arranged in a series of interrupted concentric circles, mounted between the wall of the casing and the month sheet, a month name disc rotatably mounted in the casing, and means for rotating the cancellation disc, said month sheet and back having cut away portions for engagement with the alignment lugs on the casing.

2. In a perpetual calendar of the type set out, the combination of a casing, said casing having an aperture in the front thereof, alignment lugs on the casing, a detachable back on the casing, a cancellation disc having cancelling lines arranged in a series of interrupted concentric circles and rotatably supported by the front of the casing, a month sheet visible through the aperture in the front of the casing and also provided with apertures, and a month name disc rotatably mounted on the rear of the casing, the names thereon being visible through one of the said apertures in the month sheet, said month sheet and back having cut away portions for engagement with the alignment lugs on the casing, and means for rotating the cancellation disc.

3. A perpetual calendar as claimed in the foregoing claim 1 comprising a casing having a housing for the reception of a segmental portion of the cancellation disc, whose axis is relatively lowered with respect to its normal position in the casing by bending the disc out of its normal plane, the bent out segmental portion lying within the housing.

4. In a perpetual calendar, the combination of a casing including a detachable back and having an aperture in the front, a month name disk rotatably supported on the back of the casing, a month sheet visible through

the aperture in the casing and formed with apertures for viewing the month names on the month name disk, and a rotatable cancellation disk having cancelling lines arranged in a series of interrupted concentric circles mounted in front of the month sheet.

5. A calendar of the type set out having a casing provided with an aperture, means therein having day delineations thereon, a cancellation disk movable over said delineations, and a part extending at an angle from the casing, said part deflecting and maintaining the lower portion of said disk out of its normal plane.

15 6. A calendar of the type set out having a casing provided with an aperture, means therein having day delineations thereon, a flexible cancellation disk in the casing having knob means journaled in the casing adjacent the front and operable to move the disk over the delineations, and a base extending rearwardly from the casing, said base deflecting and maintaining the lower portion of said disk out of its normal plane.

25 7. A calendar according to claim 6 wherein said delineations are carried by a flexible element in the rear of said disk, said element having the lower portion deflected and maintained deflected like said disk and by said base.

30 8. A calendar of the type set out having a mounting provided with an aperture, a sheet having a plurality of calendar members thereon, said sheet being shiftable to different positions relatively to the mounting to selectively dispose said calendar members in registry with said aperture, each calendar member having day delineations in curvilinear formation, alignment means on the mounting for setting said sheet to align the respective calendar members with the aperture, and a rotatably mounted cancellation disk provided with relatively opaque markings curvilinearly arranged correspondingly to said delineations, rotation of the disk causing the marking progressively to move over the said delineations.

35 9. In a perpetual calendar of the type set out, the combination of a casing, said casing having an aperture in the front thereof, a detachable back on the casing, alignment lugs on the casing, a month sheet visible through the aperture in the casing, a cancellation disk having cancelling lines arranged in a series of interrupted concentric circles, mounted between the wall of the casing and the month sheet, a month indicating means located in the casing, and said month sheet and back having cut away portions for engagement with the alignment lugs on the casing.

40 10. In a perpetual calendar of the type set out, the combination of a casing, said casing having an aperture in the front thereof, a detachable back on the casing, a month sheet visible through the aperture in the casing,

means on the casing for aligning the month sheet, a cancellation disk having cancelling lines arranged in a series of interrupted concentric circles, mounted between the wall of the casing and the month sheet, a month name disk rotatably mounted in the casing, and means for rotating the said cancellation disk.

45 In testimony that I claim the foregoing as my invention, I have signed my name this 13 day of January, 1931.

50 HARCOURT CORY HANROTT.
